CLAIM

The ornamental design for a portable display, as shown and described.

DESCRIPTION

FIG. 1 is a top, front and right side perspective view of a portable display showing my new design;
FIG. 2 is a top, rear and left side perspective view thereof;
FIG. 3 is a front elevational view thereof;
FIG. 4 is a rear elevational view thereof;
FIG. 5 is a left side view thereof;
FIG. 6 is a right side view thereof;
FIG. 7 is a top plan view thereof;
FIG. 8 is a bottom plan view thereof;
FIG. 9 is a bottom, rear and left side perspective view showing the portable display in a folded state;
FIG. 10 is an enlarged view of portion 10 in FIG. 1;
FIG. 11 is an enlarged view of portion 11 in FIG. 2;
FIG. 12 is an enlarged view of portion 12 in FIG. 4; and,
FIG. 13 is an enlarged view of portion 13 in FIG. 9.
The oblique shade lines in the drawings represent a reflective surface.
The broken lines in the drawings illustrate portions of the portable display which form no part of the claimed design.
